INVENTOR.

John Simonet

United States Patent Office.

JOHN SIMONET, OF FLATBUSH, NEW YORK.

Design No. 4,019, dated May 10, 1870.

DESIGN FOR A MUFF.

The Schedule referred to in these Letters Patent and making part of the same.

To all whom it may concern:

Be it known that I, JOHN SIMONET, of Flatbush, in the county of Kings and State of New York, have invented a new and original Design for a Muff; and I do hereby declare that the following is a full, clear, and exact description thereof, which will enable others skilled in the art to make and use the same, reference being had to the accompanying drawing forming part of this specification.

The nature of my design is fully represented in the accompanying drawing, to which reference is made.

I claim as my invention—

A design for muff, having a broad dark stripe on each end, and narrow stripes between them, all relieved by intermediate stripes of a light shade, as shown.

The above specification of my invention signed by me this 9th day of March, 1870.

JOHN SIMONET.
